United States Patent Office

Des. 182,159
Patented Feb. 25, 1958

182,159

HAND EXERCISER

Henry A. Blake, West Newton, Mass., assignor to Blake Industries, Inc., a corporation of Massachusetts

Application March 13, 1957, Serial No. 45,241

Term of patent 14 years

(Cl. D83—1)

Fig. 1 is a front elevation of a hand exerciser embodying the instant design;

Fig. 2 is a top view thereof;

Fig. 3 is a side elevation thereof;

Fig. 4 is a rear elevation thereof;

Fig. 5 is a bottom view thereof; and

Fig. 6 is a fragmentary side elevation with parts broken away for purposes of illustration.

I claim:
The ornamental design for a hand exerciser, substantially as shown.
